Specification for Design.

Patented Aug. 22, 1916.

Application filed July 14, 1916. Serial No. 109,394. Term of patent 14 years.

To all whom it may concern:

Be it known that I, SENECA G. LEWIS, a citizen of the United States, residing at Greensburg, in the county of Westmoreland and State of Pennsylvania, have invented a new, original, and ornamental Design for Rubber Vehicle-Tires, of which the following is a specification, reference being had to the accompanying drawing, forming part thereof.

Figure 1 is a plan view of a portion of a tire, showing my new design, and Fig. 2 is a side elevation of the same.

I claim:

The ornamental design for a rubber vehicle tire as shown.

SENECA G. LEWIS.
